UNITED STATES PATENT OFFICE.

JOHN H. GRAYSON, OF ATHENS, OHIO. ASSIGNOR TO THE J. H. GRAYSON MANUFACTURING COMPANY, OF ATHENS, OHIO, A CORPORATION OF OHIO.

GAS-HEATER.

1,371,477.

Specification of Letters Patent. Patented Mar. 15, 1921.

Application filed December 13, 1919. Serial No. 344,736.

To all whom it may concern:

Be it known that I, JOHN H. GRAYSON, a citizen of the United States, residing at Athens, in the county of Athens and State 5 of Ohio, have invented certain new and useful Improvements in Gas-Heaters, of which the following is a specification.

The present invention relates to gas heaters, particularly to what is known as the 10 radiator type. As is well known, heat is principally propagated by convection and radiation. Gas heaters of the type referred to operate, as the name indicates, in the main, on the principle of radiation. The gas 15 flame is passed through a body of refractory material forming a mantle and thereby heated to a glowing condition. The greater part of the heat energy is absorbed by the material of the mantle and radiated substantially as 20 fast as it is absorbed. A considerable portion of the available heat energy, however, is carried out by the products of combustion into the flue and wasted.

It is the principal object of the invention 25 to provide a gas heater in which a very high percentage of the heat of combustion is utilized for the purpose for which it is intended and only a relatively small percentage is allowed to escape as waste.

30 My invention, briefly stated, consists in using a secondary radiating system in the path of the products of combustion for the purpose of absorbing and radiating such available heat energy which would normally 35 go to waste in heaters of the usual kind.

For a fuller understanding of the invention reference is had to the accompanying drawings, in which—

Figure 1 is a side elevation of a gas 40 heater, a part being shown in section;

Fig. 2 is a front view of a heater section, parts being removed to show the principal feature of the invention.

Fig. 3 is a sectional view of a back brick 45 formed according to the invention; and

Figs. 4 and 5 are front and rear views of a radiator section.

In the drawings 1 represents a gas burner tube which may be of any suitable or preferred form, 2 being the manifold for feeding the gas to a plurality of burners. Upon 50 a support 3 are assembled a back brick 4 and a series of radiators or mantles 5 in front thereof.

55 The front face of the back brick is slightly

overhanging, forming an angle of approximately five degrees with the vertical, and the rear surface of the radiator 5 is upwardly receding to the same extent to fit against the back brick. 60

The radiator 5 has two preferably imperforate side walls 6 and a front wall 7 and a rear wall 8, both of suitable lattice work. The rear wall is preferably provided with slits 8' and small projections 8''. 65

The front face of the back brick is formed with a relatively large number of diagonally extending channels, or grooves 9 defining outwardly tapering studs or projections 10 arranged in staggered relation. This feature 70 is principally identified with the invention.

The operation is as follows:

The burner flame passes upwardly into the radiator and heats the material of the radiator to glowing condition. The products of 75 combustion escape partly through the rear wall 8 of the radiator and in passing upwardly through the zig-zag shaped channels 9 they envelop the projections 10 and give up part of the sensible heat energy thereto. 80 The absorbed heat is again radiated forwardly through the interstices of the radiators 5 and is propagated into the room together with the heat given off by the radiator *per se*. The projections 10 thus form in 85 effect a secondary radiating system in addition to the primary system of the radiators 5.

The projections 10 thus continuously absorb and radiate heat which would otherwise be lost. They at the same time act as 90 baffle elements to retard the flow of the heated gases upwardly into the flue and thereby additionally promote the abstraction of heat from the products of combustion.

Due to the baffling effect of the projections 95 10 the hot gases are more uniformly distributed throughout the interior of the radiator 5.

The projections 10 also act as deflectors. As the front face of the back brick 4 is overhanging, the hot gases in passing upwardly 100 partly strike the tapered studs and are deflected forwardly against the rear wall 8 of the radiator or even through the slits 8' thereby transferring more heat to the radiator. 105

The channels 9 allow the products of combustion to expand and give the flame full freedom and thereby promote complete combustion of the gaseous mixture.

By the arrangement described the products of combustion passing out through the top of the radiator and through the channels 9 are relatively cool. The greater part 5 of the sensible heat has been thrown out, principally by radiation, to the front into the room.

The form of the channels and the resulting studs or projections may of course be 10 varied. Preferably they should, however, be so formed that the projections have outwardly tapering surfaces operating to deflect the gases forwardly.

I prefer to form recesses 10' in the projections 15 defining thin walled radiating elements in order to promote the rate of radiation therefrom. By this or similar means the proportions may be locally heated to a glowing condition and the rate of radiation 20 correspondingly increased.

I claim:

1. In a gas heater, the combination of a radiator and a back brick having on its front surface projections formed to define 25 thin walled radiating elements positioned to effectually intercept the flow of the hot gases.
2. In a gas heater, the combination of a radiator and a back brick having on its front surface 30 projections arranged in staggered relation and formed to define thin-walled radiating elements.
3. In a gas heater, the combination of a

radiator and a back brick having on its front surface outwardly tapering projections arranged in staggered relation and formed to define thin-walled radiating elements. 35

4. In a gas heater, the combination of a radiator and a back brick having on its front 40 surface projections formed at their ends to define thin-walled radiating elements.

5. In a gas heater, the combination of a radiator and a back brick therefor, the front 45 surface of the back brick being forwardly inclined from bottom to top and having projections defining thin-walled radiating elements and the rear wall of the radiator being similarly inclined to fit against the 50 brick.

6. In a gas heater the combination with a radiator, of a back brick having a channeled surface defining projections, said projections being recessed to form relatively 55 thin-walled radiating elements.

7. In a gas heater the combination with a radiator, of a back brick having thin-walled 60 projections adapted to be locally heated to glowing condition.

8. In a gas heater the combination with a radiator, of a back brick having cupped projections.

In testimony whereof, I affix my signature.

JOHN H. GRAYSON.
